UNITED STATES PATENT OFFICE.

JOSEPH SCHNEIBLE, OF WEEHAWKEN, NEW JERSEY.

APPARATUS FOR THE TREATMENT OF REFRACtORY WATER.

No. 902,766.

Specification of Letters Patent.

Patented Nov. 3, 1908.

Application filed April 5, 1907. Serial No. 366,485.

To all whom it may concern:

Be it known that I, JOSEPH SCHNEIBLE, a citizen of the United States, residing in Weehawken, Hudson county, in the State of New Jersey, have invented certain new and useful Improvements in Apparatus for the Treatment of Refractory Water, of which the following is a specification, reference being had to the accompanying drawings, forming a part hereof.

In Letters Patent of the United States No. 820,524, granted May 15, 1906, there is shown and described an apparatus for adding to refractory water on its way to a boiler or other containing vessel or conductor talc-like or other material intended to modify the water and particularly to prevent or break up the concretion of mineral constituents which, if the water is unmodified, sometimes forms scale. The apparatus shown in said Letters Patent is designed to be operated by the flow of the water on its way to the boiler or other vessel or conductor, and operates satisfactorily where the flow is great enough to actuate the apparatus. Other apparatus has been designed, especially for use where the flow of water is comparatively limited and the support for the apparatus is in more or less constant motion, as in the case of a locomotive, in which the movements of the support for the apparatus are made to actuate the devices by which the desired material is added to the water.

The present invention has for its object to provide an apparatus for the same general purpose, but adapted to meet other conditions of use and particularly to provide for the actuation of the devices which grind or reduce to a finely divided condition the matter to be added to the water and effect or permit the addition thereof to the water by means which are not dependent upon the movement of the support or directly upon the flow of the water. Such means, however, most conveniently comprise some moving part of the pump by which the water is delivered.

The invention will be more fully explained hereinafter with reference to the accompanying drawings in which it is illustrated as embodied in a convenient and practical form.

In the drawings—Figure 1 is a view in side elevation showing an ordinary reciprocating boiler feed pump with the devices for

adding the desired material to the water in operative relation therewith. Fig. 2 is a detail view in section on the plane indicated by the line 2—2 of Fig. 1. Fig. 3 is a detail view in section on the line indicated by the line 3—3 of Fig. 2.

In the embodiment of the invention illustrated in the drawings a reciprocating boiler feed pump, of ordinary construction, is shown, the same comprising a steam cylinder *a*, a pump cylinder *b* with outlet *c* and usual valve gear *d* operated by a piston rod which is not shown.

Connected with the outlet *c* of the pump is the apparatus by means of which the grinding or reduction and addition to the feed water of the talc-like or other desired material are accomplished. This apparatus may be of any construction suited to the conditions of use. As shown it comprises a container *e* for the material which is to be added to the water, a hopper *f* forming the lower portion of the container, and a suitable grinding or reducing and transferring roll or like device *g* mounted in the discharge outlet *f'* of the hopper *f*, for reducing and transferring, in small quantities and in a finely divided condition, material from the bulk in a more or less coarse condition in the container *e* to the water chamber *f'* through which the water flows from the outlet *c* of the pump.

The transferring and reducing or grinding roll *g* is fixed upon a shaft *h* mounted in suitable bearings in the walls of the water chamber *f'* and is driven by means external to the water conduit. As shown the shaft *h* is provided with a ratchet wheel *h'* which is engaged by a pawl or dog *i* carried by an arm *i'*. The latter is mounted to swing on the shaft *h* and is connected by a link *k* with an arm *d'* of the valve gear *d*. Operating connections might be established between the reducing and transferring device and any other moving part of the pump or pump mechanism, as may be most convenient under the conditions of use, and indeed the device might be actuated from any convenient source of power external to the water conduit or, in other words, by means not actuated by the flow of water to or through the water treating apparatus and not directly dependent thereon. The use of the feed pump, however, is preferable, both on account of its convenience and because, with its use, attention to the operation of the transferring de-

vice is unnecessary since the transferring device then operates only when the pump is in operation and in proportion to the speed of the pump.

5. Various modifications of details of construction and arrangement will suggest themselves under different conditions of use and it is therefore understood that the invention is not limited to the precise construction and arrangement shown and described herein.

I claim as my invention.

1. In a device of the class described, a container adapted to receive material in a relatively coarse condition and having an outlet opening, means adjacent said opening for reducing the material contained therein to a finely divided condition, a conduit extending past said opening and said reducing means and into which the finely divided material is discharged, a pump for causing water to flow through said conduit, and a connection between a moving part of said pump and said reducing mechanism whereby said reducing mechanism is operated by and in unison with said pump.

2. In a device of the class described, a vertically arranged container adapted to receive material in a relatively coarse condition and having an outlet opening at its lower end, means adjacent said opening for reducing the material contained in said receiver to a finely divided condition, a conduit extending past said opening and said reducing means and into which the finely divided material is discharged, a pump for forcing water through said conduit, and a connection between a moving part of said pump and said reducing mechanism whereby said reducing mechanism is operated by and in unison with said pump.

3. In a device of the class described, a vertically arranged container adapted to receive material in a relatively coarse condition and having an outlet opening at its lower end, a

rotary grinding roll adjacent said opening for reducing the material contained in said receiver to a finely divided condition, a conduit extending past said opening and said grinding roll and into which the finely divided material is discharged, a pump for forcing water through said conduit, and a connection between a moving part of said pump and said rotary grinding roll whereby said grinding roll is operated by and in unison with said pump.

4. In a device of the class described, a vertically arranged container adapted to receive material in a relatively coarse condition and having an outlet opening at its lower end, a rotary grinding roll adjacent said opening for reducing the material contained in said receiver to a finely divided condition, a conduit extending past said opening and said grinding roll and into which the finely divided material is discharged, a pump having reciprocating parts and adapted to force water through said conduit, a reciprocating link operated from a moving part of said pump, and mechanism intermediate said reciprocating link and said rotary grinding roll whereby said grinding roll is operated by said link.

5. An apparatus for the treatment of refractory water etc., comprising a conduit for the water, a container for the material to be added to the water, a grinding roll for transferring the material in a finely divided condition from the container to the water in the conduit, a feed pump and operative connections including a pawl and a ratchet wheel on the shaft of the grinding roll for actuating the grinding device through the movements of the pump.

This specification signed and witnessed 85 this 27th day of March, A. D., 1907.

JOSEPH SCHNEIBLE.
